UNITED STATES PATENT OFFICE.

ISAAC LEIBOWITZ, OF BROOKLYN, NEW YORK.

CALENDAR.

Application filed January 22, 1924. Serial No. 637,678.

To all whom it may concern:

Be it known that I, ISAAC LEIBOWITZ, a citizen of the United States, residing at Brooklyn, in the county of Kings and State of New York, have invented certain new and useful Improvements in Calendars; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in calendars, and the invention has for its principal object to provide a novel construction of calendar pad and holder therefor.

The invention has for a further object to provide a novel construction of calendar pad, comprising a set of monthly leaves, mounted on a rotatable member having finger pieces at its periphery, whereby the pad may be shifted to position a given date indication of a top leaf in desired disclosed position; said calendar pad being supported in a novel holder having a means for disclosing to view the said given date indication, combined with means cooperating with the finger pieces of the rotatable member supporting the calendar pad, so that stops are provided for limiting the rotative motion of the pad when said rotatable member is actuated by the finger of the user.

Other objects of this invention, not at this time more particularly enumerated, will be clearly understood from the following detailed description of the same.

With the various objects of this invention in view, the same consists in the novel calendar device hereinafter described; and, the invention consists, furthermore, in the novel arrangements and combinations of the various devices and parts, as well as in the details of the construction of the same, all of which will be hereinafter more fully described in the following specification, and then finally embodied in the appended claim.

The invention is clearly illustrated in the accompanying drawings, in which:—

Figure 1 is a front elevation of the novel calendar device, made according to and embodying the principles of this invention; Figure 2 is a vertical longitudinal section

through the same, taken on line 2—2 in said Figure 1; Figure 3 is a fragmentary vertical longitudinal section, similar to that shown in Figure 2, but with the calendar pad removed from the holder; Figure 4 is a fragmentary rear face view of the holder; Figure 5 is a front face view of the calendar pad; Figure 6 is a fragmentary rear face view of the calendar pad; Figure 7 is a side or edge elevation of the calendar pad; Figure 8 is a vertical section through the calendar pad, taken on line 8—8 in Figure 7; and Figure 9 is a fragmentary view of a detached monthly leaf of the calendar pad.

Similar characters of reference are employed in all of the hereinabove described views, to indicate corresponding parts.

Referring now to said drawings, the reference character 10 indicates a back-plate upon which the calendar pad is mounted; 11 indicates a rotatable member; and 12 indicates a pad of monthly calendar leaves, the center portions of which are preferably adhesively secured together, and in turn adhesively secured to said rotatable member 11. The marginal portion 13 of each calendar leaf is free, and is initially connected with the main body of the leaf by a circular perforated line 14, which defines the line of separation whereby said free marginal portion 13 of the leaf may be torn away from the main body thereof, and from the pad, at the desired time. The face of said marginal portion 13 of each leaf is divided into a plurality of radial panels, each panel containing a date and day indication for the month to which a particular leaf is devoted. Said rotatable member 11 is provided at its periphery with a plurality of radially extending finger pieces 15, which are respectively aligned with the respective date panels, and which project outwardly beyond the periphery of the pad of calendar leaves. Said pad of calendar leaves together with the rotatable member 11 upon which the pad is secured, is rotatably affixed to said back-plate 10 by means of a pintle, rivet or the like 16, and the upper marginal portion of said back-plate 10 is cutaway, as at 17, to provide a clearance notch or indentation giving access to the finger pieces 15 of said rotatable member 11. The lower end of said back-plate extends downwardly beyond the calendar pad and rotatable member 11 to provide a tongue 18.

The novel holder for the calendar pad

carrying means, constructed as above described, consists of a main body 19, provided in its upper portion with a receiving pocket or chamber 20, open at its upper end, and 5 into which said calendar pad carrying means may be inserted. Extending downwardly into the body of said holder 19 from the bottom of said pocket or chamber 20, and in alignment with the rear wall of the latter, is 10 a receiving slot or socket 21 in which the tongue 18 of said back-plate 10 is received, when the calendar pad carrying means is inserted within said pocket or chamber 20.

The front wall of said main body 19 is 15 cutaway at its upper marginal portion, at a point intermediate the sides of said body, to provide an opening 22 with which the data bearing panels of the calendar leaves may be successively disclosed to view, when 20 the calendar pad is turned. The side margins of said opening 22, at their upper ends, are also cut back to provide stop-shoulders 23, which serve to limit the finger actuated movement of the rotatable member 11 in a 25 manner subsequently described. In like manner, the rear wall of said main body 19 is correspondingly cutaway to provide similar stop-shoulders 23'.

Said main body 19 with its calendar pad 30 devices in place, is preferably supported in the manner of an easel, and to this end there is suitably secured to the back of said main body 19 a prop-member 24 (see Figures 2 and 3).

35 The face of said main body may be suitably inscribed with a yearly calendar display arranged in panels together with such additional data, as may be found convenient to tabulate and display, all as shown more particularly in Figure 1 of the drawings.

In making use of the novel calendar device above described, it will be apparent, that a finger piece 15 of the rotatable member 11 projects upwardly above the opening 22 in the front wall of said holder 19 intermediate the stop-shoulders 23 and 23', and that the calendar pad will be so positioned as to expose one of the date bearing panels of the top calendar leaf through said opening 22. To shift the calendar pad so as to register with the opening 22 the panel of the calendar leaf bearing a succeeding or next ensuing date indication, the user places a finger against the exposed finger-piece 15 and presses the same to the left, or in the direction of the arrow α shown in Figure 1, thereby rotating the member 11 and the calendar pad 12 connected therewith. The rotary movement thus imparted 60 to the member 11 and pad 12 is limited and determined by the stop-shoulders 23 and 23', for as the finger presses against the finger-piece 15, the finger moves therewith until it contacts with said stop-shoulders 65 which, being immovable, prevent further

application of moving force to the engaged finger-piece 15, and consequently thereupon arrests the rotary movement of the calendar pad and member 11. The stop-shoulders are so spaced relative to the normal stationary position of the exposed finger piece, that a movement of a degree corresponding to the width of a date panel of the calendar leaf is alone permitted, and consequently the imparted and permitted rotation is just sufficient to move the succeeding date panel from behind the wall of the body 19 to a position registered with and exposed in the opening 22 of the latter, while at the same time moving the previously exposed date panel to concealed position behind said wall.

When it is desired to disclose a calendar leaf for a succeeding month, the back-plate 10 is removed from the pocket of the holder, and the detachable marginal date bearing portion of the proceeding monthly leaf is torn away along the line of perforations, thus exposing the date bearing portion of the ensuing or succeeding month, whereupon the back-plate 10 with the calendar pad and rotatable member is again inserted into the pocket of the holder ready for renewed operation and use relative to the newly exposed calendar leaf.

From the above description, it will be quite evident, that this invention provides a novel calendar construction, which while simple and cheap to manufacture, is very easily manipulated, and which provides self-registering means in the form of said finger-pieces and stop-shoulders which assures, when manipulated, that each succeeding date panel of an exposed calendar leaf will always be properly and neatly registered with and exposed through the opening 22 of the holder member.

I am aware that some changes may be made in the arrangements and combinations of the various devices and parts, as well as in the details of the construction of the same, without departing from the scope of this invention as set forth in the foregoing specification, and as defined in the appended claims. Hence, I do not limit my invention to the exact arrangements and combinations of the said devices and parts as described in said specification, nor do I confine myself to the exact details of the construction of said parts as illustrated in the accompanying drawings.

I claim:—

A calendar device, comprising a holder member provided in its upper end with a downwardly extending pocket terminating at its lower end in a receiving slot contiguous to the rear wall of said pocket, a removable back-plate within said pocket having its lower end engaged in said receiving slot, a rotatable member mounted on said

back-plate, a pad of monthly calendar leaves fixed to said rotatable member having radially arranged date bearing panels, said rotatable member having radial fingers 5 projecting from its periphery in correspondence with said date bearing panels of said calendar leaves, and said holder member having in its front wall an opening to display a date bearing panel registered therewith and in its front and rear walls 10

indented notches to give access to a finger for actuating said rotatable member and calendar pad.

In testimony, that I claim the invention set forth above I have hereunto set my hand 15 this 19th day of January, 1924.

ISAAC LEIBOWITZ.
